UNITED STATES PATENT OFFICE

147,323

DESIGN FOR A DESK TYPE CIGARETTE LIGHTER

Helmut Erlanger, San Francisco, Calif.

Application April 19, 1946, Serial No. 128,754

Term of patent 7 years

(Cl. D48—27)

To all whom it may concern:

Be it known that I, Helmut Erlanger, a citizen of the United States of America, residing at San Francisco, in the county of San Francisco and State of California, have invented a new, original, and ornamental Design for Desk Type Cigarette Lighter, of which the following is a specification, reference being had to the accompanying drawing, forming a part thereof.

Fig. 1 is a front elevation of a desk type cigarette lighter, showing my new design, and

Fig. 2 is a side elevation of the same.

I claim:

The ornamental design for a desk type cigarette lighter, substantially as shown.

HELMUT ERLANGER.
